(57) CLAIM

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

4.-5. Shoe

4.1 : Front

4.2 : Back

4.3 : Top

4.4 : Bottom

4.5 : Right

4.6 : Left

4.7 : Perspective

5.1 : Front

5.2 : Back

5.3 : Top

5.4 : Bottom

5.5 : Right

5.6 : Left

5.7 : Perspective

The portions of the shoe shown in yellow form no part of the claim.

1 Claim, 14 Drawing Sheets
(14 of 14 Drawing Sheet(s) Filed in Color)
